[57] CLAIM

The ornamental design for a paper roll holder for toilet paper or similar article, as shown and described.

DESCRIPTION

FIG. 1 is a perspective view of a paper roll holder for toilet paper or similar article showing my new design;

FIG. 2 is a front elevational view thereof;

FIG. 3 is a rear elevational view thereof;

FIG. 4 is a side elevational view taken from the left of FIG. 2;

FIG. 5 is a side elevational view taken from the right of FIG. 2;

FIG. 6 is a bottom plan view thereof;

FIG. 7 is a top plan view thereof; and

FIG. 8 is an exploded perspective view thereof.
